UNITED STATES PATENT OFFICE.

JAMES EDGAR LEE, OF GRAND HAVEN, MICHIGAN.

PRINTING-PRESS.

1,367,193.

Specification of Letters Patent.

Patented Feb. 1, 1921.

Application filed November 22, 1919. Serial No. 339,910.

To all whom it may concern:

Be it known that I, JAMES EDGAR LEE, a citizen of the United States of America, residing at Grand Haven, in the county of Ottawa and State of Michigan, have invented certain new and useful Improvements in Printing-Presses; and I do hereby declare the following to be a full, clear, and exact description of the invention, such as will enable others skilled in the art to which it appertains to make and use the same.

This invention relates to a printing press. It is an object and purpose of the present invention to make various improvements and perfections in a printing press of the type shown by the patent to Stonemetz, No. 884,302, issued April 7, 1908. The invention is particularly concerned with improvements in the inking mechanism through which ink is supplied to and distributed over the type carried by the reciprocating table of the press. One particular feature of improvement in connection with the inking mechanism is directed to novel means for increasing or diminishing the supply of ink to be spread on the type, said means being very quickly and easily operated and set from in front of the printing press. Still further objects in connection with the inking mechanism are to provide means for holding the distributing and vibrator rollers and for quickly and easily adjusting the same toward each other and toward or away from the type, together with a mechanism for more solidly and substantially holding the reciprocating table which carries the printing form against any vibrating movements which would make the printing defective. A still further object of the invention is to provide a novel and simple means for attaching a covering on the cylinder of the press and particularly in the method of assembling the devices. A still further object of the invention is to provide means for holding the fingers which take the printed sheets and carry them to the delivery table of the press against movement while the machine is running, which at times is desirable. Various other objects and purposes than those specifically enumerated will appear fully and in detail as understanding of the invention is had from the following description taken in connection with the accompanying drawings, in which;

55 Figure 1 is a perspective view of the press

taken from one side and slightly in front thereof.

Fig. 2 is a similar perspective view taken looking at the opposite side and from in the rear.

60 Fig. 3 is a fragmentary vertical section taken through the press at the front portion thereof and looking to the rear illustrating the mechanism for operation of the reciprocating table.

65 Fig. 3^a is a fragmentary section in side elevation, taken lengthwise of the table and showing the mechanism for reciprocating the same.

70 Fig. 4 is a fragmentary side view of the mechanism for adjusting the ink supply to the inking mechanism of the press.

75 Fig. 4^a is a section at the end of the inking roller against which the ink directly engages, the roller and the sprocket and ratchet wheels thereon, being shown in elevation.

Fig. 5 is a front view of the setting mechanism for the ink supply.

Fig. 6 is a side elevation thereof.

80 Fig. 7 is a side elevation of two of the adjustable roller carrying devices.

Figs. 8 and 9 are end elevations thereof, the supporting frame means therefor being shown in section.

85 Fig. 10 is an elevation showing the means for supporting the vibrator roller and associated distributing rollers; and

Fig. 11 is a view looking against the left hand end of the structure shown in Fig. 10.

90 Like reference characters refer to like parts in the different views of the drawings.

In the construction of the press a supporting frame is provided having sides 1 which are made up of a plurality of horizontal rails and vertical parts and which are connected by a plurality of cross members two of which, 2 and 3, are shown in Fig. 1 as connecting the sides at their lower ends at the front end of the machine and near the middle thereof. A table 4 for carrying the form is mounted for reciprocation on the supporting frame, rollers 5 being interposed between this table and horizontal bed pieces 1^a on which the rollers move. The table is carried back and forth below the cylinder 6 which is rotatably mounted above the table. A short distance beyond the side of the frame 1 the cylinder shaft is equipped with a gear 7 which is in mesh with a gear 8, this gear together with a smaller gear or pinion 100

105 105

110

9, being secured at the end of a shaft 10 which is mounted on the supporting frame below the cylinder. Pinion 9 is in mesh with a gear 11 which is secured at the end of 5 a transverse shaft 12 and which extends from one side 1 to the other of the supporting frame. Two gears 13 and 14 are mounted on the shaft 10 and are adapted to rotate in opposite directions at equal speeds using 10 the same mechanism as in the Stonemetz patent heretofore noted. A grooved cam 15 on the shaft 12 serves to turn a frame 16 back and forth about its pivotal mounting shown in Fig. 3, this lever at its upper end 15 slidably engaging with a movably mounted member 17 which is mounted in the under side of the table 4 and to which a rack 18 is attached so that with the rotation of shaft 12 the rack 18 alternately engages with the 20 two gears 13 and 14. As a consequence the table 4 is reciprocated. This is not a new movement as it is fully shown in the Stonemetz patent. As the table moves with considerable speed it is necessary that a means 25 be used to gradually bring it to a stop at the ends of its movement and start it back in the opposite direction. To this end short racks 19 are fixed to the under side and at each end of the table 4 with which a gear sector 20 is adapted to alternately engage. An arm 21 is pivotally mounted at 22 at its lower end between the ends of a supporting beam 23 carried by the cross members 2 and 3 as shown in Figs. 1 and 3a. A link 21a 30 connects the upper end of the arm 21 with gear 14 at a distance from the center of the gear. The gear sector 20 is made at the upper end of an arm 24 which is loosely mounted on shaft 12. A link 24a connects the upper end of arm 21 with the arm 24. It is apparent that with the rotation of the gear 14 a reciprocatory movement is given to the link 21a causing the arm 21 to rock back and forth on its pivot 22 and likewise the arm 40 45 24 has a similar rocking movement through the connection of link 24a. The sector 20 engages with the short racks 19 as the table approaches the end of its movement in either direction, slows the table down gradually 50 and starts it moving in the opposite direction. This movement is also old in the Stonemetz patent. However, the support of the front arm 21 in the present construction is much more solid and substantial and is an insurance against vibration. This is a matter 55 of considerable importance in this connection as the teeth of the gear segment and the racks must be timed to engage exactly; otherwise there will be chattering and vibration of the table 4 with a consequent imperfect printing. The beam 23 is of exceptional strength and rigidity, much more so than is necessary for the mere support of the arm 21 and insures against any undesired vibration and imperfect connection of 60 65

the gear segment 20 with the rack 19. Consequently the support of the arm 21 is a very practical improved feature of my invention.

A lever 25 extends in front of the press 70 and at its front end has connection with an upwardly extending rod 26a which is attached to one end of a chain 26 used to operate an inking roller as will be hereafter described. Lever 25 is pivotally mounted 75 between its ends on a bracket 27 depending from one of the sides 1 of the supporting frame. The lever at its inner end is equipped with a roller 28 adapted to ride against an eccentric 29 fixed on the shaft 12. 80 The roller is normally kept in contact with the eccentric by a spring 30 connected to the lever and frame as shown in Fig. 4. The lever adjacent its front end passes through a slot 31 made in a member 32 attached to 85 the front end of the frame and in its lowermost position may be placed underneath a lug 33 which projects into the slot, in which position the roller 28 is raised above the eccentric and is not acted upon by the eccentric at any time in its movements. It is designed that this lever 25 may be held against going above any one of a plurality of positions between its uppermost and lowermost 90 positions shown in Fig. 5. To accomplish 95 this a plate 34 is pivotally mounted at one end at 35 on the member 32, the edge of the plate being provided with a consecutive series of notches 36. A pin 37 is carried at the end of a spring arm 38 secured to the 100 plate 34 and is adapted to enter any one of the series of openings 39 made in the arc-shaped portion 40 which is cast integral with the member 32. By pulling out on the head of pin 37 so as to disengage the pin from the 105 notch 39 in which it is located, plate 34 may be freed for movement. The lever 25 may be then depressed at its forward end and the plate 34 moved to any desired position being held therein by the engagement of the pin 110 37 with a notch 39. The lever 25 when released cannot go to the uppermost position shown in Fig. 5 but will be stopped by its engagement with the plate 34 at one of the notches thereof. 115

It is apparent that when the lever 25 is in its uppermost position roller 28 follows the eccentric 29 continuously with a consequent continuous up and down movement of the front end of the lever and operation of the chain 26. This chain 26 passes over a sprocket wheel 41 and thence downwardly toward the bracket 27 being connected to said bracket by a coiled spring 42 as shown in Fig. 4. This spring 42 may 120 be made sufficiently strong that spring 30, heretofore described may be dispensed with, the roller 28 being held against eccentric 29 through spring 42 alone. The sprocket wheel 41 is loosely mounted on the end of 125 130

a shaft 43 and alongside of a ratchet wheel 44 which is fixed to said shaft. A dog 45 is mounted on and moves with the sprocket wheel, being adapted to engage with the 5 ratchet wheel in one direction of movement of the sprocket wheel. The shaft 43 is at the end of an inking roller 46 against which the printer's ink is placed in a suitable trough 46^a and by means of which on its rotation, 10 ink is delivered to various transfer and distributing rollers and thence to the type carried in the printer's form on the table 4. When the plate 36 is thrown to its extreme 15 position as shown in Fig. 5 with a continuous up and down movement of the lever 25 and a continuous rotation of the sprocket wheel 41 back and forth on the shaft 43, and in one direction of the movement of the sprocket wheel, the greatest amount of ink 20 is distributed. When the lever 25 is placed under the projection 33 there is no movement thereof and no ink distribution. With every restriction of the movement 25 of the lever 25 in an upward direction caused by bringing the plate 34 more and more into its path of movement, the rotation of the inking roller 46 is correspondingly 30 decreased with a corresponding decrease in the supply of ink to the type. This is evident from the fact that during part of the rotation of the shaft 12 roller 28 will not engage with the cam 29 and there is only a 35 partial downward and upward movement of the lever 25 and a partial movement of the sprocket wheel 41 with every rotation of the shaft 12.

With this construction the supplying of ink to the type may be very closely controlled and a greater or less amount of ink 40 supplied as desired. If the printing is faint, a little additional movement of the lever 25 is given by moving the plate 34 upwardly; if too heavy the plate 34 is moved in the opposite direction with a consequent decrease 45 of ink supply; and because of the large number of stations in the edge of the plate 36 the supply of ink may be controlled very closely. This is a feature of great importance in printing as either too great or too 50 little amount of ink is particularly disastrous to good printing.

A shaft 47 is mounted above and at one end of the receiving table to which the printed sheets are delivered. On this shaft 55 a plurality of fingers 48 are fixed being adapted to take the printed sheet from the cylinder 6 and swing through an arc of approximately 180 degrees to deliver the same to the table. A sprocket wheel 49 is fixed 60 on one end of the shaft. A sprocket chain 50 has one end attached to a coiled spring 51 which at its opposite end is connected to the supporting frame of the machine. The opposite end of the chain has connection 65 to the upper end of a rod 52 which at its

lower end is pivotally connected to a bent lever 53, said lever being pivotally mounted on the supporting frame of the machine as shown in Fig. 2. The sprocket chain runs over the sprocket wheel. A cam 54 is secured on the end of the shaft 12 and serves to operate the lever 53 once with each rotation of the shaft whereby the fingers 48 are moved from receiving to delivering position and back, the spring 51 being of sufficient strength to normally hold the fingers in one position. If at any time it is not desired that the fingers shall operate, it is necessary merely to insert a pin through one of the links of the chain 50 whereupon the 75 spring will hold the pin against the housing 50^a and stop the spring from exerting its force and shaft 47 cannot turn beyond the point where it is stopped. This is desirable sometimes and the construction shown and 80 described permits this.

In the ink distribution, use is made of distributing and vibrator rollers which are mounted in front of the printing drum 6. It is desirable that the distributing rollers 90 may be adjusted toward or away from the type and also adjusted with respect to the vibrator roller. Also that all of the rollers may be removed whenever necessary for 95 cleaning or replacement and that the cost of manufacture of the brackets for mounting said rollers shall be as small as possible so that one mounting device for all of these rollers and also for the distributing rollers at the front end of the machine may be used 100 on either or both sides of the frame. The vibrator roller 63 has a projecting shaft 61 at each end which passes through a bushing 64 mounted at the upper end of a bracket 62 which is permanently connected one at 105 each side of the supporting frame. The bracket 62 is slotted as indicated at 63^a in Fig. 10. From the bushing 64 a handle 65 extends downwardly alongside the bracket, being equipped at its lower end with a spring 110 actuated catch which may be moved outwardly by grasping the knob 66. Normally, in the positions shown in Figs. 10 and 11, the handle and the bushing are locked 115 against turning movement but by withdrawing the spring pressed lock pin, the handle may be turned through an arc of 180 degrees and the vibrator roller 63 removed from its supporting bracket. This vibrator roller is adapted to be in contact with two distributive rollers 75. The supports therefor comprise posts 67 each at its upper end being provided with an offset elongated extension 67^a. The posts are mounted on horizontal portions of the frame 1 at each side of the 120 machine and each rests on a rod 68 threaded at its lower end through and extending downwardly below said horizontal portion of the frame. On each a nut 69 having a ratchet upper face is secured, the turning 125

130

of which will thread the rod 68 through the lower flange of the supporting rail and either raise or lower the posts 67, depending on the direction that it is turned. A pin 70 pressed downwardly by spring 71 engages with the ratchet face of the nut and normally holds the same against accidental movement.

- Each of the offset portions 67^a at the upper end of posts 67 is longitudinally slotted as indicated at 72. A roller carrying socket 73 is mounted on said offset portion 67^a, a set screw 74 passing through the slot 72 and threaded through the socket member 73. The rollers 75 have projecting shaft portions 15 at each end which seat in sockets 75^a, the same being inclined as shown in Figs. 7 to 10 inclusive. By operating the set screw 74 the socket members may be freed for adjustment toward or away from the bracket 62 to thus bring the pressure rollers 20 75 into proper relation and in contact with the vibrator roller 63 and the vertical adjustment of the said rollers is taken care of by operation of the nuts 69.
- 25 The brackets which support the pressure rollers are also used at the front end of the machine and in the same way except that the adjusting devices including the threaded rod 68, nut 69 and pin 70 are not used. In 30 all cases, however, it will be noted that the structure of the posts 67 is such that it is not necessary to make two separate patterns for supporting members for the rollers on the right and left hand sides of the machine.
- 35 The posts may be rotated about their vertical axes to swing the socket member 73 through an arc of 90 degrees and position the two shaft receiving pockets 76 so as to receive the shafts at the ends of the rollers.
- 40 This is a feature of construction which is valuable from the standpoint of the manufacturing cost inasmuch as the posts 67 with attached parts may be made in duplicate for both the front and rear pressure and distributing rollers and on both sides of the machine and no separate parts are needed to carry the rollers when the machine is not in use.

The constructions described have proven 50 thoroughly practical and efficient in use over a considerable period of time. The invention is mainly directed to the inking apparatus and ink distributing features of the press. Not only is there provided means for 55 spreading a greater or less quantity of ink over a form but the ink distribution is taken care of in a particularly efficient manner. The distributing rollers are easily removed and the vibrator roller which holds the inner 60 distributing rollers down may be quickly removed at any time when the press is not in operation and all of the rollers lifted above the work and held until again needed in printing. The rollers may also be readily 65 removed at any time for cleaning when it

becomes necessary or for repairing or replacement.

Various changes in minor detail of structure may be resorted to without departing from my invention which is defined in the 70 appended claims and I consider myself entitled to all modifications falling within the scope of said claims.

I claim:

1. In a printing press, inking mechanism 75 including a rotatably mounted inking roller, a ratchet wheel secured at one end of the roller, a sprocket wheel loosely mounted for rotation alongside of the ratchet wheel, a dog on the sprocket wheel to engage with the ratchet wheel and move the same in one direction of movement of the sprocket wheel, a chain passing over and engaging with the sprocket wheel, a lever pivotally mounted between its ends, means connecting one end 80 of the chain to the lever, a spring attached to the opposite end of the chain, a shaft, an eccentric on the shaft, a roller at one end of the lever adapted to ride on said eccentric, spring means tending to elevate the opposite end of the lever whereby the lever moves up and down with the rotation of the shaft, and means movable into the upward path of movement of said end of the lever and adjustable to a plurality of different positions whereby the movement of the lever and consequent rotation of the inking roller may be determined, substantially 95 as and for the purposes described.

2. In combination, an inking roller, a support therefor, on which the roller is rotatably mounted, a lever pivotally mounted between its ends on a support, a shaft, means on the shaft adapted to engage with one end of the lever to move the opposite end of the 100 lever in a downward direction, means yielding tending to move said opposite end of the lever in an upward direction, means interposed between said opposite end of the lever and the inking roller for turning the 105 inking roller during movement of the lever in one direction, and means movable into the path of upward movement of said end of the lever to limit the extent of movement of the lever and of the rotation of the 110 inking roller, substantially as described.

3. In combination, a supporting frame, a shaft thereon, means to drive the shaft, a lever pivotally mounted between its ends on the frame, means interposed between the 115 shaft and one end of the lever for moving the opposite end of the lever in one direction, yielding means for moving said opposite end of the lever in the other direction, means adjustably mounted on the supporting frame and movable into the path of movement of said opposite end of the lever to limit the extent of movement thereof, an inking mechanism, and means for operating the inking mechanism through move- 120 125 130

ments of said lever, the inking mechanism being operated to a greater or less extent, dependent upon the range of movement of the lever, substantially as and for the purposes described.

4. In a printing press, a supporting frame, a lever mounted between its ends on the frame, a shaft, means interposed between the shaft and the rear end of the lever for operating the lever about its pivot in one direction, yielding means connected to and between the lever and supporting frame normally moving the lever in the opposite direction, a member pivotally mounted on the frame and movable into any one of a plurality of positions in the path of movement of the front end of the lever whereby the movement of said lever may be limited, and inking mechanism operated by the movements of the lever, substantially as described.

5. In a printing press, a supporting frame, a lever pivotally mounted between its ends thereon, means engageable with the rear end of the lever for moving the same in one direction about its pivot, a member having a slot therein through which the front end of the lever passes, a notched member pivotally mounted on the first member at one end of the slot and adapted to be moved to a plurality of positions with respect to said first member and thereby diminish the effective length of the slot through which the front end of the lever may have movement, means normally tending to move the lever against said notched member, and inking mechanism operatively connected with the lever to be operated thereby in proportion to the movement of the lever, substantially as and for the purposes described.

6. In a printing press, a supporting frame, a lever pivotally mounted between its ends thereon, means for periodically moving the lever about its pivot so as to lower the front end thereof, spring means tending to elevate the front end of the lever, a member attached to and located at the front end of the support having a vertical slot through which the front end of the lever passes, a notched plate pivotally mounted on said member at the upper end of the slot, means for adjustably securing said plate in any one of a plurality of positions with the plate passing across the slot so as to limit the upward movement of the lever to a greater or less extent, and an inking mechanism operatively connected with the lever and operable amounts proportionate to the range of movement of the lever, substantially as described.

7. In combination the elements defined in combination in claim 6 and a lug at the lower end of the member extending into the slot and underneath which said lever may

be placed and held, substantially as described.

8. In a printing press, a supporting frame, an inking roller against which the ink is adapted to contact rotatably mounted at the front end of the frame, a ratchet wheel at one end of and movable with the roller, a sprocket wheel loosely mounted at the end of the roller and alongside the ratchet wheel, a dog carried by the sprocket wheel adapted to engage with the ratchet wheel and turn the same and the connected roller on movement of the sprocket wheel in one direction, a bracket depending from the frame, a spring connected at one end thereto, a sprocket chain attached to the opposite end of the spring and passing over the sprocket wheel, a lever pivotally mounted between its ends on said bracket, means connecting the opposite end of the sprocket chain with the front end of the lever, a shaft, means to drive the same, an eccentric on the shaft, a roller on the rear end of the lever adapted to ride against said eccentric, a member having a vertical slot therein secured at the front part of the frame, the front end of the lever passing through said slot and a notched plate pivotally mounted on said member at the upper end of the slot and adapted to be turned so as to cross the slot and progressively diminish the effective length for movement of the lever therein with each downward adjustment of the notched member, substantially as and for the purposes described.

9. In a printing press, a support including parallel side rails, a table mounted for reciprocation on the support between said rails, a bracket secured to each rail at each side of the table, one of said brackets being slotted downwardly from its upper end, a bushing located in said slot, a handle depending from the bushing, a spring pressed locking pin passing through the lower end of the handle and into the bracket, a vibrator roller located between the brackets and mounted at its ends in the bushings, and distributing rollers mounted one at each side of and below the vibrator roller and adapted to contact with the same and with type carried in a printer's form on the table, substantially as described.

10. In a printing press, a supporting frame including spaced apart horizontal rails, a table mounted for reciprocation between said rails and adapted to carry a printer's form, a vibrator roller detachably mounted on and above the rails and over the table transversely thereof, posts one at each side of the vibrator roller on each rail, means for adjusting said posts vertically, a socket means adjustably mounted at the upper ends of said posts and adjustable toward or away from each other, said socket

- means carrying distributing rollers, one at each side of and below and in contact with the vibrator roller, and means to hold the socket means in any position to which adjusted, substantially as described.
11. In a printing press, a supporting frame including spaced apart horizontal rails, a table mounted for reciprocation between said rails and adapted to carry a printer's form, a vibrator roller detachably mounted on and above the rails and over the table transversely thereof, posts one at each side of the vibrator roller on each rail, a rod threaded through the rails against the lower end of each post, a nut having a notched upper surface secured to the lower end of each rod, spring pressed pins, one for each nut carried on the rails and adapted to engage with the notched surfaces of the nuts, socket means adjustably mounted at the upper ends of said posts and adjustable toward or away from each other, said socket means carrying distributing rollers, one at each side of and below and in contact with the vibrator roller, and means to hold the socket means in any position to which adjusted, substantially as described.

12. A supporting member for distributing rollers of printing presses comprising a post formed at its upper end with a lateral offset portion, said portion having a longitudinal slot therein, a socket member located directly

above the upper end of the post and formed to support one end of a distributing roller, and a screw passing through the slot and threaded into the lower portion of the socket member to adjustably bind the socket member against the offset portion of the post, substantially as and for the purposes described.

13. A support for the ends of distributing rollers in printing presses comprising a cylindrical post adapted to be mounted at the sides of a form carrying table in a printing press, said post at its upper end being formed with an integral offset portion in which a horizontal slot is made, a socket member located directly over the upper end of the cylindrical portion of the post and provided in its upper end with a shaft receiving socket located at an angle to the vertical, and a screw passing through said slot in the offset portion of the post and threaded into the lower part of the socket member, substantially as and for the purposes described.

14. A construction containing the elements in combination claimed in claim 13, said socket member at its upper end being provided with shaft receiving pockets or sockets located at right angles to the first mentioned socket, substantially as described.

In testimony whereof I affix my signature
JAMES EDGAR LEE
